US0D1094773S

(12) **United States Design Patent** (10) **Patent No.:** **US D1,094,773 S**
(45) **Date of Patent:** **** Sep. 23, 2025**

(54) **INSTRUMENT**

(71) Applicant: **Meso Scale Technologies, LLC.**,
Rockville, MD (US)

(72) Inventors: **Jacob N. Wohlstadter**, Palm Beach
Gardens, FL (US); **Rodger Darin
Osborne**, Stuart, FL (US); **Sandor
Kovacs**, Middletown, DE (US); **Aaron
Leimkuehler**, Upper St. Clair, PA (US);
Cecilia Zimmerman, Clarksburg, MD
(US); **Jules VanDersarl**, Gaithersburg,
MD (US)

(73) Assignee: **Meso Scale Technologies, LLC.**,
Rockville, MD (US)

(**) Term: **15 Years**

(21) Appl. No.: **29/963,613**

(22) Filed: **Sep. 18, 2024**

Related U.S. Application Data

(60) Continuation of application No. 29/926,279, filed on
Jan. 30, 2024, now Pat. No. Des. 1,048,461, which is
a continuation of application No. 29/901,082, filed on
Aug. 29, 2023, now Pat. No. Des. 1,016,325, which
is a continuation-in-part of application No.

CLAIM

The ornamental design for an instrument as shown and
described.

DESCRIPTION

FIG. 1 is a front perspective view of an instrument showing
our new and ornamental design;

FIG. 2 is an alternate front perspective view thereof;

FIG. 3 is an alternate front perspective view thereof;

FIG. 4 is an alternate front perspective view thereof;

FIG. 5 is a front elevation view thereof;

FIG. 6 is a side elevation view thereof;

FIG. 7 is a side elevation view thereof;

FIG. 8 is a top plan view thereof;

FIG. 9 is a rear elevation view thereof;

FIG. 10 is a rear perspective view thereof; and,

FIG. 11 is a bottom rear perspective view thereof.

(Continued)

The broken lines illustrate portions of the instrument that form no part of the claimed design.

1 Claim, 11 Drawing Sheets

Related U.S. Application Data

29/786,021, filed on May 28, 2021, now Pat. No. Des. 999,398, which is a division of application No. 29/675,738, filed on Jan. 4, 2019, now Pat. No. Des. 921,222.
